UNITED STATES PATENT OFFICE.

WILLIAM W. WOODRUFF, OF ARDMORE, PENNSYLVANIA, ASSIGNOR TO STRAWBRIDGE & CLOTHIER, OF PHILADELPHIA, PENNSYLVANIA, A CORPORATION OF PENNSYLVANIA.

PAPER-FOLDING DEVICE.

Application filed March 13, 1928. Serial No. 261,206.

This invention relates to means for folding long strips of paper, such as the recording strips or tapes of cash registers and similar recording devices.

5 The principal object of this invention is to produce a device by which these long strips may be reduced to flat bundles or packages of uniform dimensions in order that they may be conveniently filed for future reference; and in order that the strips may be more conveniently handled by auditors, or other persons, who are required to inspect them after they have been removed from the recording devices in which they 10 have been used.

These recording strips are usually printed on but one side only, by mechanism in the recording device in which they are used. Each strip is placed in the recording device 20 in the form of roll and assumes the form of a roll after the printing mechanism of the recording device has recorded sales and other information on the strip.

By the use of my invention the rolled strips, after being removed from the recording device, may be quickly folded, accordion fashion, into flat packages of uniform dimensions, each comprising a plurality of successively connected leaves or layers of 30 uniform length which, if desired, might be subsequently bound into book form.

The strips in their uniformly folded state consume a minimum amount of space for a given number of strips, permitting stand- 35 ardized economical filing in suitable cabinets. The book-like leaves formed by folding the strips in this manner, may, when the records are being audited or otherwise inspected, be turned and read in the same 40 manner as the leaves of a bound book, each book-like leaf comprising a pair of adjacently positioned layers connected at their one end so that the printed matter appears on the opposite sides of the leaf and the 45 blank sides of the two layers of which the leaf is composed lying against each other. The opposite end of each of said layers is connected to the adjacent layer of each of the adjacent leaves thus formed.

50 The details of my invention will be disclosed hereinafter, reference being had to the accompanying drawings, of which:

Figs. 1 and 2 are respectively a side and end elevation of a preferred form of the invention.

In Figs. 1 and 2, I have illustrated the preferred form of the invention, which comprises a base structure 25, composed of sheet metal bent to the desired shape. Secured to each of the opposite longitudinal 60 sides 26, 26 of the base structure 25 is a side frame 27, 27 each comprise a pair of vertically extending members 28, 28^a connected at their upper ends, longitudinally of the device, by horizontally extending members 29. The upright members 28, 28 and 28^a, 28^a of the frames 27, 27 are connected by transversely extending members 30, 30. Suitable braces 31, 31 connect the longitudinal members 29 70 and the vertical members 28 and 28^a of each side frame 27. The side frames 27, 27 connected by the transverse members 30, 30 form a rigid superstructure on the base structure 25. 75

At each side of the device, intermediate the vertical members 28 and 28^a thereon and secured to the side members 26 of the base structure 25, is a longitudinally extending plate 32 between the opposite ends of which 80 and the adjacently disposed vertical members of the superstructure are formed slots 33, 33 which extend substantially perpendicular to the upper flat surface of the base structure 25. The slots 33, 33 are adapted 85 to receive fold-forming elements in the form of circular rods 19. On each of the vertical members 28, 28^a and located above the slots 33 is a bracket 34. The brackets 34, 34 at each end of the superstructure are 90 adapted to support a supply of fold-forming rods 19. The elements comprising the base and superstructure thereon may be secured together by any suitable means which as shown at 39 in the present instance consists 95 of spot welding.

The upper members 29, 29 of the superstructure are notched as indicated at 35 for the reception of a spindle 36 on which a roll α^1 of the strip material α is rotatably 100 mounted. To one of the transversely extending frame members 30 is secured one end of a flat spring 37, by means of a screw or bolt 38, the opposite end of the spring 37 being adapted to bear on the periphery 105 of the roll α^1 and thereby retard rotation on the spindle 36. At one end of the base structure 25 is a paper clip or other holding means 40 which is adapted to hold the free end of the strip α during the folding operation. 110

In operation a roll x^1 is positioned on the superstructure of the device as illustrated in the drawings. The free end of the strip x is then led downwardly between the side frames 27, 27 of the superstructure and gripped by the fastener 40, the general position of the strip being indicated at x^2 in Fig. 1. One of the fold-forming rods 19 is then lifted from the supply, supported by the brackets 34 at the end A of the device, and carried in a direction indicated by the arrow A¹, and thereafter deposited in the slot 33 at the end B of the superstructure. In its movement the rod 19 engages the strip and carries it from the position illustrated at x^2 to a position on and parallel to the upper flat surface of the base structure 25, thus the first layer of the package is positioned. One of the fold-forming rods 19 is then taken from the supporting brackets 34 at the end B of the superstructure and carried along the path generally indicated by the arrow B¹, being finally deposited in the slots 33, 33 at the end A of the superstructure. In passing from the brackets 34 at the end B to the slots 33, 33 at the end A, the rod engages the strip x and carries it into a position to form a second layer parallel to the first layer and to the flat surface of the base structure 25. This operation is repeated until the entire strip is laid upon the base structure 25 in parallel folds or layers, the slots 33, 33, at the opposite ends of the device receiving the fold-forming rods 19 in alternate succession. After the entire strip has been folded the rods 19 may be withdrawn from the folds transversely of the device as above described, the plates 32 maintaining the folds in position while the rods are being withdrawn.

I claim:

1. In a device for folding rolled strip material, a base structure, a superstructure carried by said base structure and adapted to rotatably support a roll of said material, a plurality of fold-forming elements, and means provided in said superstructure for receiving said fold-forming elements in alternate succession.
2. In a device for folding rolled strip material, a base structure, a superstructure carried by said base structure and adapted to rotatably support a roll of said material, a plurality of fold-forming elements, means provided in said superstructure for receiving said fold-forming elements in alternate succession, and means for holding one end of the strip during the folding operation.
3. In a device for folding rolled strip material, a base structure, a superstructure carried by said base structure and adapted to rotatably support a roll of said material, a plurality of fold-forming elements, means provided in said superstructure for receiving said fold-forming elements in alternate suc-

cession, means for holding one end of the strip during the folding operation, and means carried by said superstructure for retarding the rotation of the roll during the folding operation.

4. In a device for folding rolled strip material, a base structure, a superstructure carried by said base structure and adapted to rotatably support a roll of said material, a plurality of fold-forming elements, means provided in said superstructure for receiving said fold-forming elements in alternate succession, means for holding one end of the strip during the folding operation, means carried by said superstructure for retarding the rotation of the roll during the folding operation, and means on said superstructure for supporting said fold-forming elements in a manner to facilitate said folding operation.

5. In a device for folding rolled strip material, a base structure having a substantially flat surface, a superstructure, comprising side frames secured to said base structure, each side of said superstructure being provided adjacent each of its opposite ends with a slot extending perpendicular to the said flat surface of said base structure, means carried by said side frames for supporting a roll of said material therebetween, and a plurality of fold-forming rods adapted to be extended transversely of the strip and to be brought individually and successively into engagement therewith, and to be deposited in the slots of said superstructure in alternate succession.

6. In a device for folding rolled strip material, a base structure having a flat surface, a superstructure comprising a pair of similar and transversely aligned frames secured to and extending longitudinally of said base structure, each side of said superstructure having a slot adjacent each of its opposite ends and extending perpendicular to the flat surface of said base structure, means carried by said side frames for rotatably supporting a roll of said material therebetween, means for securing the free end of said strip to said base structure, and a plurality of fold-forming rods extending transversely of the device and adapted to be brought individually into contact with said strip and deposited in alternate succession in the transversely aligned slots at the opposite ends of said superstructure.

7. In a device for folding rolled strip material, a base structure having a flat surface, a superstructure comprising a pair of similar and transversely aligned frames secured to and extending longitudinally of said base structure, each side of said superstructure having a slot adjacent each of its opposite ends and extending perpendicular to the flat surface of said base structure, means carried by said side frames for ro-

tatably supporting a roll of said material therebetween, means for securing the free end of said strip to said base structure, a plurality of fold-forming rods extending 5 transversely of the device and adapted to be brought individually into contact with said strip and deposited in alternate succession in the transversely aligned slots at the opposite ends of said superstructure, and 10 brackets on said side frames for supporting said rods in a position to facilitate the folding operation.

8. In a device for folding rolled strip material, a base structure having a flat surface, a superstructure comprising a pair of 15 similar and transversely aligned frames secured to and extending longitudinally of said base structure, each side of said superstructure having a slot adjacent each of its 20 opposite ends and extending perpendicular to the flat surface of said base structure, means carried by said side frames for rotatably supporting a roll of said material therebetween, means for securing the free 25 end of said strip to said base structure, a plurality of fold-forming rods extending transversely of the device and adapted to be brought individually into contact with said strip and deposited in alternate succession in

the transversely aligned slots at the opposite 30 ends of said superstructure, and means carried by said superstructure for retarding the rotation of said roll.

9. In a device for folding rolled strip material, a base structure having a flat surface, a superstructure comprising a pair of 35 similar and transversely aligned frames secured to and extending longitudinally of said base structure, each side of said superstructure having a slot adjacent each of its 40 opposite ends and extending perpendicular to the flat surface of said base structure, means carried by said side frames for rotatably supporting a roll of said material therebetween, means for securing the free 45 end of said strip to said base structure, a plurality of fold-forming rods extending transversely of the device and adapted to be brought individually into contact with said strip and deposited in alternate succession 50 in the transversely aligned slots at the opposite ends of said superstructure, brackets on said side frames for supporting said rods in a position to facilitate the folding operation, and means carried by said superstruc- 55 ture for retarding the rotation of said roll.

WILLIAM W. WOODRUFF.
